(57) **CLAIM**

The ornamental design for a coating film transfer tool, as shown and described.

DESCRIPTION

FIG. 1 is a perspective view of the transfer tool;
FIG. 2 is a front elevational view of the transfer tool;
FIG. 3 is a rear elevational view of the transfer tool;
FIG. 4 is a top plan view of the transfer tool;
FIG. 5 is a bottom plan view of the transfer tool;
FIG. 6 is a left side elevational view of the transfer tool;
FIG. 7 is a right side elevational view of the transfer tool;
FIG. 8 is a front elevational view of the transfer tool;
FIG. 9 is a cross-sectional view taken along line A-B-C-D of the transfer tool;
FIG. 10 is a front elevational view with a cap open of the transfer tool;
FIG. 11 is a front elevational view reduced in size with a cover open of the transfer tool;
FIG. 12 is a front elevational view showing transparent portion in gray of the transfer tool; and,
FIG. 13 is a cross-sectional view taken along line A-B-C-D showing transparent portion in gray of the transfer tool.
